(57) **CLAIM**

The ornamental design for a display screen or portion thereof with animated graphical user interface, as shown and described.

DESCRIPTION

A portion of the disclosure of this patent document contains material to which a claim for copyright is made. The copyright owner has no objection to the facsimile reproduction by anyone of the patent document or the patent disclosure, as it appears in the Patent and Trademark Office patent file or records, but reserves all other copyright rights whatsoever.

FIG. 1 is a front view of a display screen or portion thereof with animated graphical user interface;

FIG. 2 is a front view of the second image thereof;

FIG. 3 is a front view of the third image thereof;

FIG. 4 is a front view of the fourth image thereof;

FIG. 5 is a front view of the fifth image thereof;

FIG. 6 is a front view of the sixth image thereof; and,

FIG. 7 is a front view of the seventh image thereof.

The appearance of the image transitions sequentially between the images shown in FIGS. 1-7. The process or period in which an image transitions to another forms no part of the claimed design. The broken line showing of the remainder of the graphical user interface forms no part of the claimed design.

Design is embodied in a display screen for use with a computer.
